UNITED STATES PATENT OFFICE.

JOHN A. MATHES, OF SAN DIEGO, CALIFORNIA.

KEROSENE INCANDESCENT LAMP.

No. 823,733.

Specification of Letters Patent.

Patented June 19, 1906.

Application filed December 13, 1904. Serial No. 236,652.

To all whom it may concern:

Be it known that I, JOHN A. MATHES, a citizen of the United States, residing at San Diego, in the county of San Diego and State of California, have invented certain new and useful Improvements in Kerosene Incandescent Vapor Lamps, of which the following is a specification.

This invention relates to lamps for burning kerosene for lighting purposes, and more particularly to that class of lamps in which kerosene is vaporized and the vapor burned in connection with a mantle, and has for its primary object the provision of extremely simple, compact, durable, positive, and efficient means for vaporizing kerosene and burning the vapor, intermingled with air, in connection with a mantle, thus producing an extremely powerful and white light.

10 A further object of the invention is to provide such a construction as to bring all portions of the mixing-chamber close under the bottom of the mantle and in intimate relation therewith.

15 A further object of the invention is to provide a combined generating and air-mixing apparatus in which the generating or vaporizing chamber shall be located in close relation to the air and vapor-mixing chamber, and close to the bottom of the mantle and the mixing-chamber and vaporizing-chambers being so arranged with relation to each other that the vaporizing-flame may be utilized to thoroughly heat not only the walls 20 of the vaporizing-chamber, but all portions of the walls of the air-mixing chamber.

25 A further object of the invention is to provide the vaporizing and air-mixing apparatus in such form and so arranged that the generating or vaporizing chamber, while receiving sufficient heat from the burning flame of the burner to generate dry gas or vapor, yet the heat will not be sufficiently great to prevent the proper mixture of the air and vapor 30 in the mixing-chamber.

35 A further object of the invention is to provide the vaporizing or generating chamber at one side of the mixing-chamber, so that the initial heating of the vaporizing-chamber by an alcohol flame or other means can be readily attained without in any manner interfering with the vaporizing-chamber or other part or parts of the lamp, and, further, in the provision of a covering or hood over the vaporizing-chamber, so that in the initial heating of the vaporizing-chamber all heat from the

alcohol-flame or other means can be localized upon the generator to readily heat the same, and which hood will also retain the heat from the vaporizing portion of the flame upon the 60 vaporizing-chamber when the burner is in operation.

Other and further objects and ends in view will hereinafter appear from the detail description of construction and operation. 65

The invention will be more readily understood by reference to the accompanying drawings, forming part of this specification, and in which—

Figure 1 is a plan view of a lamp embodying my invention, the mantle and mantle-holder being removed. Fig. 2 is a side view thereof, a portion of the mantle being broken away and the vaporizing and air-mixing apparatus being shown in vertical section on line $x^2 x^2$ of Fig. 1. Fig. 3 is a sectional view on line $x^3 x^3$ of Fig. 1. Fig. 4 is a sectional plan view on the line $x^4 x^4$ of Fig. 2. 70 75

As shown in the drawings, 2 represents a casing which is preferably oblong in form 80 with a rounded outer end and within which is formed the mixing-chamber 3. This casing 2 is provided with a closed top and bottom and at one side is provided with a series of perforations or slots 4 and with an opening 5 in its top above the perforated or slotted side 4. The wall and casing 2 is extended upwardly into a flange 6 above this opening 5. As the series of perforations or slots 4' are extended downwardly along one side of 90 the casing and the vaporizing-tube 10 is arranged sidewise to and transversely of this side burner, I am able to accomplish two highly-important results. First, I am able to provide a burner of great compactness, 95

which is highly desirable in a lamp, and, second, I am able to bring all portions of the outer surface of the vaporizing-tube 10 between the inlet and outlet of the vaporizer into direct contact with the flame from the side burner 4. This is of extreme importance in the vaporization of kerosene, and it is equally of importance that the inlet end of the vaporizing-tube should not be directly in contact with the flame, as it is very desirable 105 not to project the cold oil flowing into the vaporizing-tube into too great heat at the point of its introduction into the tube. Otherwise carbonization is liable to stop up the inlet in the vaporizing-tube and clog the inlet end of 110 the vaporizing-tube. The vaporizing-tube 10 provides a single straight unitary vaporiz-

ing-chamber wherein equal vaporization of all of the kerosene is insured, and by the provision of the clean-out plug 23 this single straight unitary vaporizing-chamber may be 5 most readily cleaned of all deposits of carbon and impurities carried by the oil. It has been found in the use of kerosene - vapor 10 stoves that it is highly important to provide against such deposits in the vaporizing-chamber, and to accomplish this desired result in the most simple manner I have provided a single straight vaporizing-tube having a single unitary and straight vaporizing-chamber, the vaporizing-tube being arranged 15 alongside of and transversely to the downwardly-extending slotted portion of the burner, so that I am able to combine the advantages of such a single straight unitary vaporizing-chamber and a unitary flame at the 20 main burner and the vaporizing-burner and completely surround the walls of the vaporizing-chamber with the flame. By arranging such vaporizing-tube transversely to or across the downwardly-extending side burner and 25 at the side thereof the flame comes in intimate contact with all portions of the tube, and particularly with the lower portion of the periphery thereof. A marked advantage is secured by so arranging the vaporizing-tube, 30 as if the same is arranged substantially vertical the flame is not retained against the walls of the tube and the vaporizing-chamber is not as effectually heated. Furthermore, by the construction shown the vaporization of the oil does not depend upon the 35 conduction of heat from one portion of the vaporizer in direct contact with the flame to other portions which are not in direct contact therewith, and I am also enabled to provide the greatest heat at the outlet end of the 40 vaporizing-chamber.

It is obvious that the flange 6 may be formed either integral with or separate from the casing 2. The casing 2 is also provided at 45 the side of the flange 6 with an air-draft tube 7, which may be formed either integral with or separate from the casing 2. This air-draft tube 7 has a closed top and an open bottom, and its inner wall is provided with an opening through which the air-mixing tube 8 projects into the mixing-chamber 3 of the casing, terminating a short distance from the rounded 50 end of the casing. A low wall 9 is formed at the end of the air-draft tube for the purpose hereinafter set forth, this low wall forming a shallow receptacle with the chamber 3, the wall extending slightly above the bottom of the mixing-tube 8.

10 represents a vaporizing-tube which, as 60 shown, is arranged alongside the casing 2, but preferably inclined with respect to the horizontal so that the inlet end of the tube 10 is lower than the outlet end.

The surface of the casing 2 opposite the vaporizing-tube 10 is preferably extended down,

as shown best in Figs. 2 and 3, a depression 11 being formed in the bottom of the casing 2 for this purpose, so that the perforations or slots 4 may be extended below the generating-tube 10, thus insuring the projection of flame 70 about the entire surface of the vaporizing-tube.

Preferably the lower or inlet end of the vaporizing-tube 10 is located beyond the perforations 4, so that the inlet end is outside of 75 the fire zone. The flange 6 of the casing at this side is also preferably provided with perforations 4', which extend upwardly from the perforations 4, so that the flame of the mantle is in communication with the flame burning at the perforations 4, thus insuring the burning of the vapor issuing from the perforations or slots 4 at all times while there is vapor burning at the mantle, and vice versa. 80

12 represents an oil-supply pipe leading 85 from a suitable source of supply into the lower end of the vaporizing-tube 10. This vaporizing-tube 10 is provided at its upper end with a vapor-outlet 13, which, as shown, opens opposite the inlet end of the mixing-tube 8 and across the chamber or air-draft tube 7, so that the projection of vapor from the outlet 13 in the mixing-tube 8 impels the indrawing of air in the tube 8 with the inflowing vapor. 90

17 represents a valve-casing, preferably of sufficient length to carry the packing-box away from the heat zone, so that the heat from the burner will not deteriorate the packing, and thereby causing the valve to leak. 100 Inside of this casing 17 is a valve-stem 18, which fits snugly within the casing 17 and has at its inner end a cylindrical pin-valve 16, adapted to operate in the vapor-outlet 13 of the vaporizing-tube 10. When the valve 16 105 is projected into the outlet 13, the end of the stem 18 seats against the wall of the tube 10, closing the outlet of vapor from the vaporizing-chamber 14. The stem 18 passes through a suitable packing within a packing-box 19 110 and is provided with a packing-nut 20. Toward its outer end and preferably beyond the packing-box 19 the valve-stem 18 is of enlarged diameter and provided with a thread adapted to engage in a threaded opening in 115 the flange 21. The valve-stem is preferably provided with a suitable operating head or wheel 22.

15 represents a light filling within the vaporizing-chamber 14, being shown in the 120 drawings as a series of twisted fine wires. If preferred, wire-gauze might be used in place of the wires. The object of this filling 15 is to provide against puffing of the burner due to irregularity of the vaporization within the 125 tube 10, and the use of the light filling within the tube 10 distributes the heat evenly throughout the chamber 14, thus insuring an equal and constant vaporization. The use of such light filling also prevents the de- 130

posit of carbon, as such light filling is more readily heated to the same degree as is the wall of the tube 10.

23 represents a removable plug in the lower end of the vaporizing-tube 10, by which access may be had to the chamber 14 thereof for cleaning or renewing the light filling.

Preferably the oil-supply pipe 12 is connected with the vaporizing-tube 10 by a portion 12' of smaller diameter. The object of making this portion 12' of smaller diameter than the supply-pipe 12 is to prevent the supply of oil in the pipe 12 from drawing the heat from the tube 10, as it would if the supply of oil in the tube 10 was of the same quantity as the oil in the supply-pipe 12, and also by reducing the cross-sectional area of the portion 12' the heat-conducting surface thereof is made smaller, so it can draw less heat from the vaporizing-tube.

By inclining the vaporizing-tube 10 the natural tendency of the oil as it is heated to rise is taken advantage of and the vaporizing oil rising toward the upper end of the vaporizing-tube 10 is converted into vapor before it reaches the outlet 13, thus insuring the delivery of the dry vapor through the outlet 13. By arranging the outlet 13 above the inlet into the vaporizing-tube the absolute vaporization of the oil is insured and all possibility of non-vaporized oil flowing to the outlet obviated. By thus preventing the non-volatile oil from approaching the outlet end I am also able to provide the greatest heat in the outlet end of the vaporizing-chamber, thus insuring the most complete volatilization. This is of great importance with kerosene, as the same condenses with great rapidity.

40 At the top of the opening 5 a wire-gauze 24 is provided, through which the vapor from the chamber 3 passes. This wire-gauze may be supported on the flange 6 in any suitable manner. In place of wire-gauze any suitable material may be used. Preferably at the center of the wire-gauze is formed a socket for the mantle rod or support 25. This mantle rod or support may be of the usual or of any preferred form of construction. The socket 45 for the mantle-support 25 may be formed by an inverted hollow rivet, whose prongs extend over just sufficiently on the surface of the wire-gauze to support the same in place.

26 represents the mantle, which may be of the ordinary or any preferred construction.

Preferably the supply-pipe 12 extends away from the generating-tube 10 back under the casing 2, being inclined downward.

27 represents a hood which extends out 60 from the casing 2 over the vaporizing-tube 10, this hood being extended downwardly, as shown, and being provided with an opening 28, so that the flame from the perforations or slots 4 and 4' may be in communication with 65 the flame from the mantle.

By forming the vaporizing-tube 10 at the side of the casing 2 much more ready access can be had to the tube 10 for starting the lamp in operation. It will also be noted that with this construction the side portion of the 70 flame heats the tube not only at its central portion, but also at its upper and discharge end, and that there is no cold metal with which the vapor comes in contact, so as to produce condensation.

Preferably by arranging the air-mixing tube 8 at one side of the chamber 3 provision is made for a greater commotion of the vapor in the chamber 3, so as to insure a most thorough commingling of the air and vapor 80 before the combined product passes to the mantle.

It is preferable to provide the tube 8 of such diameter as to provide an excess of air in the mixing-chamber 3, so that the vapor 85 from the vaporizing-tube 10 is commingled in the chamber 3, not only with just sufficient air to burn on the mantle 26 with a blue flame, but with a sufficient amount of air so that the flame will be of a much more intense 90 temperature, thus effectually providing against any condensation of the vapor by reason of the thorough heating of the vaporizing-tube and mixing-chamber and causing the supply of such excess air to be most 95 thoroughly commingled with the vapor.

It is thus seen that with this construction and arrangement all parts are in intimate relation to the heat zone, so that no part of the mixing-chamber is away from the heat zone, 100 thus preventing any unheated surface from being presented to the vapor which would cause condensation.

By providing a low wall 9 within the chamber 3 it is seen that in case the vaporizer should cool from any cause or the lamp be extinguished by a sudden gust of wind blowing out the light the oil forced through the tube 10 into the air-mixing tube 8 will fill the cup formed by the wall 9, and as the 110 wall 9 is slightly higher than the bottom of the tube 8 the oil will then run back out of the tube 8 and down the air-chamber 7, thus preventing a dangerous accumulation of a quantity of oil within the mixing-chamber 3. 115

Preferably the casing 2 is short, so as to provide a hollow mixing-chamber 3, the casing being of such lateral proportions as to provide sufficient capacity for the chamber. With this construction compactness is insured.

Having thus described my invention, I claim as new and desire to secure by Letters Patent—

1. An incandescent vapor-burner comprising a short, wide, hollow casing having an imperforate bottom, a top having a flanged outlet and imperforate except through said outlet, and a side or wall having a perforated portion, the perforations of which ex- 125

- tend from said outlet downwardly, a mixing-tube extending into said casing at one side of said perforated side, a vaporizing-tube having a straight unitary vaporizing-chamber 5 arranged sidewise to and transversely of said downwardly-extending perforated portion of said side, and adapted to be in direct contact with the flame therefrom, said vaporizing-tube having an inlet and an outlet, the inlet being arranged below the level of the outlet, means for supplying oil to said vaporizing-tube, said vaporizing-tube opening into said mixing-tube, and means for admitting air to said mixing-tube.
- 15 2. An incandescent vapor-burner comprising a casing having a mixing-chamber, a flanged top outlet, a side air-inlet, a downwardly-perforated side portion, a mixing-tube extending into said chamber, a straight vaporizing-tube having a unitary straight vaporizing-chamber arranged sidewise to and transversely of said downwardly-extending side portion in close proximity thereto, and having a peripheral outlet into said mixing-tube and an inlet arranged below the level of said outlet, a valve extending transverse of said vaporizing-tube controlling said peripheral outlet and means for supplying oil to said vaporizing-tube.
- 25 3. An incandescent vapor-burner, comprising a casing having a mixing-chamber, a flanged top outlet, a side air-inlet, a downwardly-extending perforated side portion, a mixing-tube extending into said chamber, a straight vaporizing-tube having a unitary straight vaporizing-chamber arranged sidewise to and transversely of said perforated side portion in close proximity thereto and having a peripheral outlet into said mixing-tube, a valve for said peripheral outlet extending transverse of said vaporizing-tube, means for supplying oil to said vaporizing-tube, a mantle on said flanged outlet, and a hood supported on said casing and extending out down over said vaporizing-tube, said hood provided with an opening allowing communication of flame between said mantle and perforated side.
- 40 4. An incandescent vapor-burner comprising a short, wide, hollow casing having an imperforate bottom, a top provided with a flanged outlet, and a side wall having a perforated portion, a mantle positioned above and extending down to said outlet, a mixing-tube extending into the chamber of said casing, a single straight vaporizing-tube having a straight unitary vaporizing-chamber arranged sidewise transverse to the length of said casing and in close proximity to the perforated portion thereof, the perforations of said side extending downward from said mantle to opposite the lower edge of said vaporizing-tube, said vaporizing-tube provided with a peripheral outlet-opening into said mixing-tube, a valve for said peripheral outlet-
- 45 let, the stem of said valve extending transversely through said vaporizing-tube, and means for supplying oil to said vaporizing-tube.
5. An incandescent vapor-burner comprising a short, wide, hollow casing having an imperforate bottom, a top provided with a flanged outlet, a side wall having a perforated portion, a mantle positioned above and extending down to said outlet, a mixing-tube 70 extending into the chamber of said casing, a single straight vaporizing-tube having a single straight vaporizing-chamber arranged sidewise and transverse to the length of said casing and in close proximity to the perforated portion thereof, all portions of said vaporizing-tube between the inlet and outlet thereof being in direct contact with the flame from said perforated side portion, the perforations of said side portion extending downwardly from said mantle to opposite the lower edge of said vaporizing-tube, said vaporizing-tube provided with a peripheral outlet opening into, said mixing-tube, a valve for said peripheral outlet, the stem of said valve extending transversely through said vaporizing-tube, a hood extending over the top and down the side of said vaporizing-tube, said hood provided with a top opening permitting the union of flame between said mantle and said perforated side portion, and means for supplying oil to said vaporizing-tube.
- 80 6. An incandescent vapor-burner comprising a casing having a central mixing-chamber, a flanged outlet therefrom, a downwardly-extending perforated portion, a mixing-tube extending into said casing at the side of said perforated side portion, a single straight vaporizing-tube having a unitary straight vaporizing-chamber arranged transverse of said downwardly-extending perforated side portion and in close proximity thereto, all portions of said vaporizing-tube between the inlet and outlet thereof being in direct contact with the flame from said perforated side portion, said vaporizing-tube having a peripheral outlet into said mixing-chamber, a valve for said peripheral outlet operating transversely of said vaporizing-tube, and means for supplying oil to said vaporizing-tube.
- 85 7. An incandescent vapor-burner comprising a short, wide hollow casing having an imperforate bottom, a top provided with a flanged outlet and a side wall having a perforated portion, a mantle positioned above and extending down to said outlet, a mixing-tube extending into the chamber of said casing at the side of said perforated portion, an air-supplying tube communicating from below said casing to said mixing-tube, a vaporizing-tube having a single straight vaporizing-chamber arranged sidewise and transverse to the length of said casing and in close proximity to the perforated portion thereof, the per-
- 90 95 100 105 110 115 120 125 130

forations of said side extending downward from said mantle to opposite the lower edge of said vaporizing-tube and extending from close proximity to the inlet end of said vaporizing-tube to close to the outlet therefrom, said vaporizing-tube provided with a peripheral outlet opening through said air-supplying tube, a valve for said peripheral outlet, the stem of said valve extending transversely through said vaporizing-tube, and means for supplying oil to the inlet end of said vaporizing-tube.

8. An incandescent vapor-burner comprising a short, wide, hollow casing having an imperforate bottom, a top provided with a flanged outlet and a side wall having a perforated portion, a mantle positioned above and extending down to said outlet, a vaporizing-tube having a single straight vaporizing-chamber arranged sidewise to and transverse to the length of said casing, and in close proximity to the perforated portion thereof, the perforations of said side extending downward from said mantle to opposite the lower edge of said vaporizing-tube, and extending from close proximity to the inlet end of said vaporizing-tube to close to the outlet therefrom, said vaporizing-tube provided with a peripheral outlet into said casing, a valve for

said outlet, the stem of said valve extending 30 transversely through said vaporizing-tube, and means for supplying oil to the inlet end of said vaporizing-tube.

9. An incandescent vapor-burner comprising a casing having a central mixing-chamber, a flanged outlet therefrom, a downwardly-extending perforated side portion, a mixing-tube extending into said casing at the side of said perforated side portion, a single straight vaporizing-tube arranged sidewise to 35 and transverse of said downwardly-extending perforated side portion and in close proximity thereto, all portions of said vaporizing-tube between the inlet and outlet thereof, being in direct contact with the flame from said 40 perforated side portion, a light anticarbonizing filling in said vaporizing-tube, means for supplying oil to said vaporizing-tube, said vaporizing-tube discharging into said mixing-tube, said mixing-tube adapted to receive air 45 from outside said casing.

In testimony whereof I have hereunto set my hand, at Los Angeles, California, this 6th day of December, 1904.

JOHN A. MATHES.
